UNITED STATES PATENT OFFICE.

LUTHER A. POWELL, OF WARRIOR, ALABAMA.

SHADE AND CURTAIN BRACKET.

1,304,705.

Specification of Letters Patent. Patented May 27, 1919.

Application filed April 7, 1917. Serial No. 160,432.

To all whom it may concern:

Be it known that I, LUTHER A. POWELL, a citizen of the United States, residing at Warrior, in the county of Jefferson and 5 State of Alabama, have invented certain new and useful Improvements in Shade and Curtain Brackets, of which the following is a specification.

This invention relates to a combined 10 shade and curtain bracket and the principal object of the invention is to provide a device of this character which will firmly hold both the shade and the curtain pole.

Another object of the invention is to 15 form each bracket of the pair of a single piece of wire bent and curved to form a complete bracket provided with a screw point for attachment to the window frame.

Another object of the invention is to 20 make the pole-supporting part with an opening therein so the curtain can pass through the same.

Another object of the invention is to provide a device of this character which is simple and durable in construction, reliable and 25 efficient in operation and one which can be manufactured and placed upon the market at a minimum cost.

The invention also consists in certain 30 other features of construction and in the combination and arrangement of the several parts, to be hereinafter fully described and specifically pointed out in the appended claim.

35 In describing my invention in detail, reference will be had to the accompanying drawings, wherein like characters denote like or corresponding parts throughout the several views, and in which:

40 Figure 1 is a view of one bracket of the pair.

Fig. 2 is a like view of the other bracket.

In these figures, 1 represents the bracket 45 for supporting the spring end of the shade roller, while 2 indicates the bracket for supporting the other end of the shade roller. As will be seen, these brackets are formed of a single piece of wire and one bracket has a circular portion 3 for supporting the curtain pole, a loop 4 for engaging the flat journal of the spring end of the shade roller and the screw point 5 to be screwed into the woodwork of the window.

The bracket shown in Fig. 2 for the other 55 side of the window frame is similar to the bracket just described with the exception

that a hole 6 is formed by looping the wire upon itself instead of the opening loop 4 shown in Fig. 1. This opening is to receive the round journal at the other end of the 60 shade roller.

The circular part 3 has an opening 7 through which the curtain extends from the pole and at this point the wire is bent down to form a nipple 8 so as to prevent this part 65 from catching in the curtain and the wire forming the other side of this opening is rounded as at 9 for the same purpose.

In forming the bracket I prefer to double the wire upon itself and to bring the 70 two pieces into close contact. At a slight distance from the point where the wire is doubled over the two wires are bent to form the nipple 8 and are then carried around in a circle to form the pole engaging part 3. 75 The outer part of the wire 10 does not complete the circle but is bent at 11 and from this point to the point where the loop 4 is formed this wire is straight, is then bent to form the open loop 4 and is then straight 80 again to the end, where it is provided with the screw point 5. The inner part 12 is carried to almost complete the circle and is then curved as at 9 and is then straightened out and extends at an angle diverging 85 from the part 10 to a point opposite the beginning of the screw point 5 on the other part, where it is bent as at 13 and carried toward the other part and is then curved around said other part as at 14. Thus, a 90 complete bracket is formed of one piece of wire, said bracket being supplied with securing means and having all projections liable to damage the curtain rounded off and also provided with means whereby the curtain 95 may be extended beyond the brackets so that all excepting a small part of the brackets is hidden from view.

It is thought from the foregoing that the advantages and novel features of my invention will be readily apparent.

I desire it to be understood that I may make slight changes in the construction and in the combination and arrangement of the several parts, provided such changes fall 105 within the scope of the appended claim.

I claim as my invention:

A curtain bracket composed of a single piece of wire having its intermediate portion doubled upon itself, said doubled portion being bent in the form of a circle to receive a curtain pole, the two parts of the 110

- wire forming the doubled portion being in contact around the major part of the circle to strengthen the circular formation, the free end of the doubled portion being
5 bent downwardly to form a downwardly extending nipple and a slot for the passage of a curtain, the outside wire of the doubled portion being separated from the inside contacting wire after completing a major part
10 of the circle to form a support for the curtain holding formation, and the inside wire

of the doubled portion being continued to almost complete the circle then bent to form an additional support for the curtain holding formation.

15

In testimony whereof I affix my signature in presence of two witnesses.

LUTHER A. POWELL.

Witnesses:

E. A. FORNEY,
J. E. BYNUM.
